UNITED STATES PATENT OFFICE

JAMES A. CHAMBERS, OF PITTSBURGH, PENNSYLVANIA.

APPARATUS FOR THE MANUFACTURE OF GLASS.

1,232,495.

Specification of Letters Patent.

Patented July 10, 1917.

Substitute for application Serial No. 829,011, filed April 2, 1914. This application filed May 9, 1916. Serial No. 96,313.

To all whom it may concern:

Be it known that I, JAMES A. CHAMBERS, of Pittsburgh, in the county of Allegheny and State of Pennsylvania, have invented a 5 certain new and useful Improvement in Apparatus for the Manufacture of Glass, of which the following is a full, clear, and exact description, reference being had to the accompanying drawing, forming part of 10 this specification, in which—

Figure 1 is a plan view, partly in horizontal section, illustrating my improved device and apparatus as adapted for use, in connection with a continuous tank furnace, 15 in the manufacture of glass; Fig. 2 is a side elevation, partly in vertical section, of a part of the same, a casting table and casting pots being substituted for the drawing kiln and drawing pots; Fig. 3 is a plan view of 20 a casting table used in the manufacture of plate glass; Fig. 4 is a side elevation of the same; Fig. 5 is a vertical sectional view of a casting pot to be used in the manufacture of plate glass; Fig. 6 is a vertical sectional 25 view of a kiln and pot from which glass cylinders are drawn in the manufacture of window glass; Fig. 7 is a side elevation of the apparatus or crane used in taking the molten glass from the tank furnace and 30 transporting it to the place of manufacture of the glass article; Fig. 8 is a plan view of the same; Fig. 9 is an end view of the tongs and the cam operating the jaws of the 35 same; Fig. 10 is a vertical sectional view showing the clutch and gear wheel that oscillates the arm of the crane; and Fig. 11 is a view showing the face of the clutch.

My invention relates to the manufacture of glass articles, such as plate and window 40 glass, and it consists in devices for supporting vessels containing molten glass in the heat of the tank furnace, and for dipping, lifting, carrying and depositing the vessels, which devices and apparatus are well adapted 45 for use in connection with an improved method of manufacturing glass invented by me and forming the subject matter of Letters Patent No. 1,186,076, dated June 6, 1916, this application being a substitution for my 50 application, Serial No. 829,011, filed April 2, 1914.

In the drawing, 2 represents a continuous tank furnace for melting the glass, in which furnace are shelves or benches 3 and 4 for holding the glass pots 5 and 6, the pots 55

being known as drawing pots, that is, shallow pots made of refractory material adapted to be set on a kiln 15, and from which pots the molten glass is drawn into cylinders to be used in the manufacture of window 60 glass, and the pots 6 being known as casting pots, that is, deeper pots adapted to contain sufficient molten glass for casting into plate glass. These vessels of refractory material, such as clay, have a capacity for absorbing 65 and retaining heat so that when preheated before dipping the molten glass from the tank furnace, the glass will not chill, as is the case when the ordinary metal ladle is used, and the glass may be allowed to properly temper therein before casting. The pot 5 and the kiln 15 are shown enlarged in Fig. 6, and the pot 6 and the casting table are shown enlarged in Figs. 3, 4, and 5. In the sides and 70 end of the furnace are doors 8 and 9 through which the pots 5 and 6 may be placed on and removed from the benches 3 and 4, the doors 9 being located at the dipping end 10 of the furnace and the doors 8 being at the melting end 11, the division being at the floaters 12. 75 At the sides of the furnace and running to the end door 9 are tracks 13 and 14, the tracks 14 extending from the end of the furnace to and between two rows of drawing kiln used in the manufacture of window 80 glass, or it may run to a casting table 16 which is used in the manufacture of plate glass. On the tracks 13 and 14 runs a trolley car 17 which may be driven by a reversible motor 25, and a double clutch 26 85 which is operated by a lever 27, the clutch being connected by suitable mechanism with the driving wheel 24 of the car. Mounted on the car 17 is a base plate 28 on which is a hollow revoluble pedestal 29 at the base of 90 which is the annular worm 30 which is driven by a motor 31 through a gear wheel 32 and a worm 33. Fitting in the pedestal 29 is the vertical cylinder 34 which is internally threaded but is prevented from turning independently of the pedestal 29 by the vertical keys 35 which extend from the outer face of the cylinder and fit within vertical splines in the interior face of the pedestal 29. Within the cylinder 34 is a screw 36, 95 the thread of which engages with the thread of the cylinder, and it is driven by means of a worm wheel 37 and a worm 38 which is so connected by suitable mechanism with the double clutch that by throwing the lever 27 100

105 110

in the opposite direction from the throw that moves the car 17 the screw 36 is caused to rotate and thus raise or lower the cylinder 34. Keyed to the top of the cylinder 34 is a housing 39 in which is mounted the hollow reciprocating shaft or arms 40, the outer surface of the part within the housing being provided with a screw thread 41, and two splines or keyways 42 for the reception of feathers or keys 43 extending inwardly from the clutch 44, thus providing means to keep the shaft 40 from turning on its axis when the clutch 44 engages with the slots 44' in the head 39' of the housing 39, 15 permitting, however, a reciprocating movement being imparted to the shaft. This reciprocating movement is imparted to the shaft 40 by means of a wheel 45 provided with a worm gear on its periphery and a screw thread in its hub, which screw thread meshes with the thread 41 on the shaft, so that by the rotation of the wheel 45 the shaft, held from rotation, is caused to move longitudinally. Power is 20 imparted to the gear wheel 45 by means of a worm 46, the gear wheels 47 and 48 and the motor 49. On the face of the wheel 45 are clutch lugs 45' adapted to engage in recesses in the face of the clutch 44, when the 25 clutch is thrown forward by the lever 41, and thus rotate the clutch and turn the shaft 40 on its axis. Within the bore 50 of the hollow shaft 40 is a rod 51 provided at one end with a hand-wheel 52 and at the other 30 end with a cam 53 which engages with the short arms 54 of a pair of tongs which are pivoted at 55 to a bracket 40' secured to the end of the shaft 40, the jaws 54' of which tongs are adapted to engage with the recesses 23 of the pots, and these jaws are 35 normally held open by the spring 56. All the motors of this crane are started and reversed by the multiple controller 57 operated by the levers 58, the current being received by the trolley 59.

The operation of my improved apparatus is as follows: In the manufacture of window glass, the batch of sand and alkali is fed into the melting end 11 of the tank furnace, 40 where it is melted by gas from the regenerative flues 21, and the molten glass flows beneath the floaters 12 to the dipping end 10. On some of the benches 4 are the pots 5 or 45 6, which are there placed to be heated to a high degree of temperature from the heat of the furnace preparatory to the dipping of the glass.

After the pots have been sufficiently heated, the trolley car 17 is run to the side 50 of the furnace opposite one of the doors 8. The arm 40 of the crane being in its retracted position and the jaws of the tongs at the end of the rod 51 being extended under the force of the spring 56, the tongs are 55 swung to face the door by means of the mo-

tor 31, the worm wheel 30 and the worm 33. The tongs are then advanced to a position where an arm of the tongs is on each side of a pot, which is done by the motor 49, the worm 46, the worm wheel 45 and the screw 41, and then the jaws of the tongs are caused to grasp the pot in the recess 23 by giving the hand wheel 52 a half turn which causes the cam 53 on the end of the rod 51 to force open the arms 54, thus closing the 75 jaws 54'.

The arm 40 carrying the pot, is then raised by the screw 36 turning in the threads of the cylinder 35 extending from the housing 39, power being imparted to the screw 80 by means of the motor 25, the worm 38 and worm wheel 37, and the clutch 26 which is operated by the levers 27.

The arm 40, carrying the pot, is then retracted and swung to its former position, 85 the car is run in front of the door 9, as shown in Figs. 1 and 2 and the pot is filled by dipping it into the molten glass by lowering the arm 40, the motor 25 being operated in the reverse direction from that described, and by tilting the pot, which is done by imparting a rotary movement to the shaft or arm 40, which is accomplished by throwing the clutch 44 in contact with the wheel 45 and starting the motor 49. After the side of the pot is below the level of the molten glass in the tank furnace, it is righted by reversing the motor 49, lifted above the level of the glass in the furnace, the car is again run to one of the doors 8 100 and the pot containing the molten glass is placed on one of the benches 4 where it is allowed to remain in the heat of the tank furnace until the molten glass in the pot has been refined, after which the pot is carried to one of the benches 22 to allow the glass to cool to a drawing or casting temperature before it is carried to the drawing kiln 15, or to the casting table.

In the manufacture of plate glass in 110 which the larger pots 6 are employed, the operation is the same as in the manufacture of window glass excepting that the pots instead of being taken to a drawing kiln are carried to a casting table where the pot may 115 be tilted and the molten glass poured on the table.

From the foregoing description those skilled in the art should be able to appreciate the advantages of my invention.

Although I have shown and described electric motors, worm gears, and other power imparting mechanism, I do not desire to limit myself thereto, as equivalent devices, which suggest themselves to those skilled in the art, may be substituted therefor without departing from my invention.

What I claim and desire to secure by Letters Patent is,—

1. In apparatus to be employed in the 130

manufacture of glass, the combination of a tank furnace having supports within the furnace for holding vessels, refractory vessels adapted to rest on said supports, and operating mechanism for grasping and handling said vessels.

2. In apparatus to be employed in the manufacture of glass, the combination of a tank furnace having supports within the furnace for holding vessels, refractory vessels adapted to rest on said supports, operat-

ing mechanism for grasping said vessels, said mechanism having a reciprocatory arm provided on one end with pivoted clamping jaws, means for actuating said jaws, and means for reciprocating said arm. 16

In testimony whereof, I have hereunto set my hand.

JAMES A. CHAMBERS.
